SLICING MACHINE

Arnold W. Lundell, 220 Byram Shore Road,
Byram, Conn.

Filed Apr. 11, 1960, Ser. No. 60,117

Term of patent 14 years

(Cl. D55—1)

FIG. 1

Des. 190,051

PAGE 2

FIG.2

FIG. 3

Fig. 1 is a front perspective view of a slicing machine with the chute in lowered position, showing my new design;

Fig. 2 is a rear perspective view thereof;

Fig. 3 is a side perspective view with the chute in raised position; and

Fig. 4 is a rear perspective view of the machine.

I claim:

The ornamental design for a slicing machine, as shown.
